[57] CLAIM

The ornamental design for a container holder for automobiles, as shown and described.

DESCRIPTION

FIG. 1 is a perspective view taken from the top, front and left side of the container holder for automobiles showing my new design;

FIG. 2 is a perspective view taken from the top, rear and right side thereof;

FIG. 3 is a left side elevational view thereof; the right side view being a mirror image;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a perspective view taken from the top, front and left side of the container holder for automobiles with the front retaining cover, rear retaining member and angle adjustment means opened.

FIG. 1

FIG. 2
